CYLINDER CLOSURE STRUCTURE

Charles Horowitz, Chicago, Harold L. Dobrikin, Highland Park, and Victor Mastis, Chicago, Ill., assignors, by mesne assignments, to Berg Mfg. & Sales Co., Des Plaines, Ill., a corporation of Illinois

Filed Sept. 13, 1961, Ser. No. 137,861

2 Claims. (Cl. 226—46)

This invention relates to closure structures and has particular relation to a means for closing the otherwise open end of a cylinder.

The invention has for one purpose the provision of means for closing an open end of a cylinder in which a piston is reciprocal in response to mechanical and fluid pressures.

Another purpose is to provide a cylinder closure structure effective to seal the closure with which it is employed against the loss of fluid pressure therefrom.

Another purpose is to provide a cylinder closure which may be easily and simply installed and removed from the cylinder with which it is employed.

Another purpose is to provide a cylinder closure which may be manually inserted and removed from a cylinder with which it is employed.

Another purpose is to provide a cylinder closure of maximum simplicity in manufacture and use.

Another purpose is to provide a cylinder closure effective to close a cylinder against the escape of fluid pressure therefrom and to serve as a thrust means against which a spring may be exerted in the operation of a piston within said cylinder.

Another purpose is to provide a cylinder and closure assembly.

Another purpose is to provide, in a cylinder having a piston reciprocal therein and yielding means for moving said piston in one direction, an assembly effective to provide for maximum ease and safety in removing said closure piston and spring from said cylinder.

Another purpose is to provide a cylinder closure structure employing a single retaining element.

Another purpose is to provide a thrust plate closure for cylinders and a single retaining element therefor, the plate having a portion in cooperation with the retaining element.

Other purposes will appear from time to time during the course of the specification and claims.

We illustrate our invention more or less diagrammatically in the accompanying drawings, wherein:

FIGURE 1 is a side elevation in partial cross-section,
FIGURE 2 is an end view,

FIGURE 3 is an end view illustrating a variant form, and

FIGURE 4 is a cross sectional side view of the closure structure shown in FIGURE 3.

Like parts are indicated by like numerals throughout the specification and drawings.

Referring now to the drawings, and particularly to FIGURE 1 thereof, the numeral 1 generally designates a cylinder. The cylinder 1 has a circumferential wall 2 and an end wall 3 at one end thereof. The opposite end of cylinder 1 is open. A fluid pressure inlet 4 is formed in the cylinder 1 and communicates with the interior thereof adjacent the end wall 3.

Reciprocally mounted within cylinder 1 is a piston assembly 5 having a hollow tubular extension 6 penetrating an aperture 7 formed in the end wall 3. A pad or other suitable element 8 is secured to the extension 6 outwardly of cylinder 1, it being understood that the element 8 may be arranged for operation of any suitable mechanism in response to movement of the piston 5 toward end wall

2

3 and resulting movement of the element 8, without departing from the nature and scope of the invention.

A suitable seal assembly 9 seals the aperture 7 again the escape of fluid pressure from the interior of chamber 1 therethrough.

The member 6 has a hollow or well 10. Mounted within the hollow 10 is a head 11. The head 11 is carried by a threaded shaft or bolt 12 which extends through an abutment ring 11a having an inner diameter less than the head 11 and through the piston 5 into a hollow threaded sleeve 13. The sleeve 13 has a nut head 14 extending outwardly of cylinder 1 and beyond a closure plate 15 positioned within the open end of cylinder 1.

The closure plate 15 is of a diameter only slightly less than the inner diameter of cylinder 1. At one point on the periphery of closure plate 15, a key 16 is formed for engagement in a slot 17 formed in the inner wall of cylinder 1 and communicating with the open end thereof, the key 16 being of a width substantially equal to that of slot 17 whereby the plate 15 is positioned against rotation in the otherwise open end of cylinder 1. A seal member, such as the O-ring 18, is positioned between the outer circumferential surface of plate 15 and is seated in the recess 19 in the inner wall of cylinder 1 to seal cylinder 1 against the escape of fluid pressure about plate 15. It will be observed that the wall of key 16 is recessed from the plate surface of plate 15 to provide for reception of seal 18.

Positioned between the piston 5 and end plate 15 is a coil spring member 20, the opposite ends of which are in contact with, and the force of which is exerted against piston 5 and end plate 15, to urge the same in opposite directions.

Inwardly spaced from the open end of cylinder 1, and formed in the inner wall thereof, is an annular groove 21 the groove 21 being immediately adjacent the recess 19 in the inner wall of cylinder 1 and, in effect, communicating therewith. A first pair of retaining rings 22, 22a, each of which is substantially semi-circular, are seated in groove 21 and each has its rear surface in contact with a portion of the seal ring 18. The retaining rings 22, 22a are in contact with substantially the entire upper and lower semi-circular halves of seal ring 18, respectively. A second pair of retaining rings 23, 23a are seated in groove 21 filling substantially the entire semi-circular left and right hand portions thereof, respectively, as viewed from the left hand portion of FIGURE 1, or as illustrated in FIGURE 2. As best seen in FIGURE 2, the rings 23, 23a are slightly less than semi-circular, the opposed ends thereof leaving a space therebetween, as indicated best at 25 in FIGURE 2.

The end plate 15 has an annular ridge 15a inwardly spaced from its periphery and of sufficient height to extend beyond the combined thicknesses of rings 22, 22a and 23, 23a, as best seen in FIGURE 1. The circular ridge 15a is inwardly spaced from the periphery of plate 15 a distance less than the width of the rings 22-23 whereby the rings 22-23a are retained with portions thereof in groove 21, and the ends thereof are retained spaced apart, as indicated at 25 in FIGURE 2, it being understood that the rings 22, 22a similarly have their ends spaced apart at diametrically opposed points spaced 90 degrees about the surface of end plate 15 from the space between opposed ends of rings 23, 23a and behind the rings 23, 23a.

The use and operation of the invention are as follows:

In assembling the device of the invention, the piston bolt 12, head 11, abutment 11a, spring 20 and plate 15 are assembled with head 11 abutting member 11a and the engagement of bolt 12 with sleeve 13 serving to clamp the spring, plate and piston in a unitary assembly. This as-

bly is then placed in cylinder 1 and moved inwardly of 5 until plate 15 reaches the position indicated in FIGURE 2. At this position, the retaining rings 22-22a 10 should not be placed in the groove 21 because of the limited space between extension or ridge 15a and the opposed face of cylinder 1. The assembly is therefore moved 15 her into cylinder 1, the slot 17, with the key 16 therein, 20 of sufficient extension to permit such inward movement of plate 15. As the ridge 15a is moved inwardly of 25 groove 21, the seal ring 18 is placed in groove 19 of cylinder 1, and the retaining rings 22, 22a are placed 30 groove 21 in position against seal 18. The rings 23, 35 are then placed in the groove 21 in overlapping relationship with rings 22, 22a, as indicated in FIGURE 2. 40 plate 15 is then permitted to return in a direction outwardly of cylinder 1 until it abuts the rear surface of 45 rings 22, 22a and engages in sealing engagement with the 50 seal 18, in the position illustrated in FIGURE 1. There- 55 r, operation of piston 5 is controlled by the fluid pressure entering at inlet 4, the presence of fluid pressure in cylinder 1 holding the piston in rearward position against 60 action of spring 20 and maintaining the spring 20 in 65 pressed configuration. Upon failure of pressure in cylinder 1 between piston 5 and end wall 3, the spring 70 is effective to move piston 5 toward end wall 3 and, through the mediacy of extension 6 and element 8, to 75 mate the mechanism with which the assembly is associated.

When it is desired to remove elements from cylinder 1 for repair or replacement, it will be realized that the spring 20, being of substantial power, would be effective, 80 with piston 5 against end wall 3, to cause a rapid dislodgment of any end plate outwardly of cylinder 1 upon use of any retaining means, thus risking the injury of personnel. Accordingly, removal of such assemblies is 85 accomplished by rotation of head 14 of sleeve 13 to 90 luce, through the mediacy of the threaded engagement with shaft 12, a retraction of shaft 12 and an abutment of head 11 with abutment 11a. When this position is reached, the members 5 and 15 are clamped together, 95 an appropriate portion 5a of piston 5 abutting an inner surface of plate 15 and holding the spring 20 compressed between members 5 and 15. It will be realized, 100 in the course of such assembly, that fluid pressure is 105 exerted from the area within cylinder 1 between piston 5 and end wall 3. With the members 5 and 15 so clamped 110 together, the assembly of elements 5, 20 and 15 may be 115 moved inwardly of cylinder 1, with the key 16 aligned to the inner end of slot 17 to remove extension 15a 120 and thus to permit the retaining rings 23, 23a to be moved toward each other, 125 spaces 25 being designed for this purpose. With the 130 rings 23, 23a moved inwardly to bring their opposed ends 135 into contact, their over-all diameter is reduced to a length 140 than the diameter of cylinder 1 and the rings 23, 23a 145 may be simply withdrawn from cylinder 1. Similarly, 150 the ridge 15a unmasking groove 21, the rings 22, 22a 155 may be simply brought together to reduce their over-all com- 160 m diameter to something less than that of cylinder 1 165 to permit simple withdrawal of rings 22, 22a. There- 170 fore, the seal ring 18 may be removed and, if desired, 175 assembled members 5, 15 and 20 may be removed as 180 it from the cylinder 1. Where, of course, the repair 185 is only a replacement of seal 18, it will be realized 190 that the assembly 5, 15 and 20 may be allowed to remain 195 in inward position in cylinder 1 until such time as a 200 seal 18 is in position, at which time the assembly described above may be repeated to reassemble the device 205 in the invention. In such reassembly, the sleeve 13 is, 210 of course, rotated in the opposite direction to move the 215 head 11 into the position illustrated in FIGURE 1, thus 220 enabling the piston 5 for movement throughout its excursion 225 within cylinder 1.

Referring now to the variant form illustrated in FIGURES 3 and 4, those parts corresponding substantially

identically to parts previously described and illustrated in FIGURES 1 and 2 are provided with the same numeral. In the arrangement of FIGURES 3 and 4, a single retaining ring 30 is seated in groove 21. While groove 19 and seal 18 are not shown in FIGURE 4, it will be realized 5 that these elements could be provided as illustrated in FIGURE 1 without departing from the scope of the invention.

The retaining ring 30 is of a thickness such as could 10 substantially fill groove 21 while allowing for ease of entering into and departure from said groove.

The member 30 is spring-like in construction, comprising 15 a type of split ring in which a central portion 31 is of a substantial width sufficient to fill groove 21 and to extend across the face of plate 15, a substantial distance toward angular ridge 15a. From the portion 31, the member 30 gradually diminishes in width in opposite curving directions as indicated at 32, 33. The opposed, 20 spaced ends 34, 35 of member 30 are enlarged in width to provide ears 36, 37 in which apertures 38, 39 may be 25 respectively formed for insertion of an appropriate tool.

In assembly and disassembly of the form illustrated in 30 FIGURES 3 and 4, elements 5 and 15 with spring 20 35 clamped therebetween by members 11, 11a, 12 and 13 are moved inwardly into cylinder 1 until ridge 15a uncovers groove 21. Member 30, with its ends 34, 35 held in juxtaposition by a suitable tool engaging apertures 38, 39, 40 is then placed in the open end of cylinder 1 and moved inwardly until member 30 is aligned with groove 21. At 45 this point the ends 34, 35 are permitted to separate further and the member 30 consequently to expand to seat within groove 21 as illustrated in FIGURE 3. The sleeve 13 is then rotated until the parts are in the position illustrated in FIGURE 1 wherein the plate 15 is held against spring 30 and spring 20 is compressed by air pressure operating against piston 5.

Whereas a preferred embodiment of the invention has 50 been illustrated and described, it will be understood that 55 further modifications will suggest themselves to those skilled in the art upon a reading of the foregoing specification. Accordingly, the foregoing description should be 60 taken as merely illustrative and not definitive, and the 65 scope of the invention should be limited only by the following appended claims.

We claim:

1. In combination, an open-ended cylinder and a closure structure therefor comprising a circular plate, said plate having a diameter less than the inner diameter of said cylinder, a seal between the peripheral edge of said plate and the inner wall of said cylinder, a groove in the inner wall of said cylinder adjacent the open end thereof and between said seal and the outer open end of said cylinder, a circular extension on said plate having a diameter less than the diameter of said cylinder and said plate, a pair of retaining ring elements, each of said ring elements being substantially semi-circular in planar section, each of said ring elements having a width greater than the radial distance between said extension and the peripheral edge of said plate, each of said ring elements having a peripheral portion seated in said groove and an inner surface in contact with said seal and with the outer surface of said plate between said extension and the inner wall of said cylinder, a second pair of substantially semi-circular retaining ring elements, said second pair of retaining elements being substantially identical to said first pair of retaining elements and having peripheral portions seated in said groove, the opposed ends of said second retaining elements being circumferentially spaced from the opposed ends of said first retaining ring elements.

2. In combination, an open-ended cylinder, a circular plate having a diameter less than the inner diameter of said cylinder and slidably mounted in the open end of said cylinder, a groove in the inner wall of said cylinder

adjacent the open end thereof, a circular ridge extending from the outer face of said plate a distance at least equal to the width of said groove, said ridge being inwardly spaced from the peripheral edge of said plate and being normally held in alignment with said groove, a first pair of retaining ring elements, each of said ring elements being substantially semi-circular in planar section, each of said ring elements having a width greater than the radial distance between said ridge and the peripheral edge of said plate, each of said ring elements having a peripheral portion seated in said groove and an inner surface in contact with the outer surface of said plate between said ridge and the inner wall of said cylinder, a second pair of substantially semi-circular retaining ring elements, said second pair of retaining elements being substantially identical to said first pair of retaining elements and having peripheral portions seated in said groove, the opposed ends

of said second retaining elements being circumferentially spaced from the opposed ends of said first retaining elements.
